UNITED STATES PATENT OFFICE.

STEPHEN J. CLULEE, OF ATTLEBORO, MASSACHUSETTS, ASSIGNOR TO BAY STATE OPTICAL COMPANY, OF ATTLEBORO, MASSACHUSETTS, A CORPORATION OF MAINE.

EYEGLASS CONSTRUCTION.

Application filed October 21, 1921. Serial No. 509,238.

To all whom it may concern:

Be it known that I, STEPHEN J. CLULEE, a citizen of the United States, and a resident of Attleboro, in the county of Bristol and State of Massachusetts, have invented an Improvement in Eyeglass Constructions, of which the following is a specification.

This invention relates to the construction of eyeglasses. One of the objects thereof is to provide a practical construction of the above nature in which the parts are securely held together under conditions of hard use. Another object is to provide a construction of the above type in which celluloid frames are reinforced in a simple and dependable manner. Another object is to provide a construction of the above type which will be inexpensive in manufacture and in which the appearance is not impaired. Other objects will be in part obvious and in part pointed out hereinafter.

The invention accordingly consists in the features of construction, combinations of elements and arrangement of parts which will be exemplified in the structure herein-after described and the scope of the application of which will be indicated in the following claims.

In the accompanying drawing in which is shown one of various possible embodiments of this invention,

Figure 1 is a rear elevation of a pair of eyeglasses;

Figure 2 is a partial plan on a larger scale, certain parts being shown in section along the line 2-2 of Figure 5 in order to disclose the construction more clearly;

Figure 3 is a cross-section along the line 3-3 of Figure 5;

Figure 4 is a cross-section taken along the line 4-4 of Figure 5; and

Figure 5 is a vertical section taken along the line 5-5 of Figure 2 and showing the central portion of the eyeglasses.

Similar reference characters refer to similar parts throughout the several views of the drawing.

In order that a fuller understanding of this invention may be had, it may first be noted that it has been attempted to mount a metallic rim member inside a celluloid eyeglass frame, that is, a frame in which not only the outer rims but bridge are of celluloid construction. Such an arrange-

ment would gain certain advantages in the 55 matter of security and strength of construction, and the avoidance of deformation due to shrinkage, but it has been found that there is a tendency of the metal member to snap out of the recess in which it is fitted 60 at a point adjacent the bridge, when the glasses are subjected to bending in use. The present invention deals chiefly with the avoidance of the above defect in a simple and practical manner without sacrifice of 65 appearance or undue cost. As herein illustratively set forth, there are a number of elements contributing to security, and it is to be understood that each of these features is of independent value although a maximum 70 of security is attained when all are employed.

It may also be noted at this point that the term "eyeglasses" is broadly employed to designate any device for mounting lenses before the eyes, and that the term "celluloid" is used broadly throughout to denote any non-metallic material adapted for use in this relation.

Referring now in detail to Figure 1 of the drawing, there is shown an eyeglass frame comprising the celluloid rim members 10 and 11 connected by a celluloid bridge 12 which is preferably integral therewith and of the usual heavy construction. Within the rim members 10 and 11 are respectively fitted metal rim members 13 and 14 resting in suitable recesses or grooves which extend about the inner surface of the outer rims as indicated in Figure 2. The outer ends of each of the rim members 13 and 14 are connected with the usual end pieces 15 and 16 to which is pivoted the temple bar 17 of any desired construction. The details of these latter members are not herein shown as they form in themselves no part of the present invention. It may be noted however that the celluloid rim members are split at the outer ends of the respective rims, terminating on the end pieces 15 and 16 and thus permitting separation to enlarge the rims when the lenses are inserted with their edges resting in the concave inner surfaces of the metal members, as shown in Figure 2.

As both sides of the eyeglasses are substantially identical, one only will be described in detail.

The metallic rim members are provided at their portions adjacent the bridge with one or more lugs 18 which may be secured thereto in any desired manner. These lugs are here shown as two in number and are formed of thin metal and bent into a corrugated or S-shape, as shown in Figure 4 of the drawing. When the metal rim member is inserted, the celluloid is heated so as to become soft and the lugs 18 forced into the end portions of the bridge to become firmly seated therein, in the position indicated in the drawing. These lugs thus tend to anchor the rim in its proper relation to the surrounding celluloid.

It is also to be noted that the groove within which the metal rims rest is deeper at the end adjacent the bridge as shown at 19 in Figure 2 of the drawing. This may be brought about by carrying the celluloid outwardly toward the center of the lens to a slightly greater extent at the bridge side of the rim and at the outer side, without detracting from the appearance of the lens.

26 The two metal rim members 13 and 14 may also be connected one with another by a metal tie wire 20 which is soldered or otherwise suitably connected with the rims at its ends and rests within a groove 21 formed in the rear side of the bridge. The celluloid may be so shaped adjacent the ends of the bridge as to interlock with this tie wire 20 and tend to prevent it from riding out from the portions of the groove or recess.

When the parts are assembled, it will thus be seen that however roughly the frames may be handled, the portions of the metal rim members adjacent the bridge are firmly anchored in position and cannot ride out of the celluloid members in which they are seated.

As various possible embodiments might be made of the above invention and as various changes might be made in the embodiment above set forth, it is to be understood that all matter herein set forth or shown in the accompanying drawing is to be interpreted as illustrative and not in a limiting sense.

50 I claim as my invention:

1. In eyeglass construction, in combination, a rim member and bridge joined thereto and both formed of non-metallic material, and a metallic rim member mounted upon

said first rim member and having a part interlocked therewith adjacent said bridge. 55

2. In eyeglass construction, in combination, a non-metallic rim member, a metal rim member inserted within a groove in said first rim member, and a projecting metal part on said metal member extending outwardly into said non-metallic member to interlock therewith adjacent the bridge of the eyeglasses. 60

3. In eyeglass construction, in combination, a rim member and bridge joined thereto and both formed of non-metallic material, a metal rim member inserted within said first rim member, and a metal part secured to said metal member and extending outwardly into said non-metallic rim member 70 adjacent its point of junction with the bridge.

4. In eyeglass construction, in combination, a rim member and bridge joined thereto and both formed of non-metallic material, 75 a metal rim member inserted within said first rim member, and a metal part secured to said metal member and extending outwardly into said non-metallic rim member adjacent its point of junction with the bridge, said projecting metal member being of thin curved form.

5. In eyeglass construction, in combination, a rim member and bridge joined thereto and both formed of non-metallic material, 85 a metal rim member fitted within said rim member, and a plurality of projecting parts secured to said metal member and extending outwardly therefrom into said non-metallic member adjacent the bridge. 90

6. In eyeglass construction, in combination, a rim member and a bridge joined thereto both formed of non-metallic material, and a metal rim member resting in a groove extending about the inner side of said non-metallic rim member said metal rim member being adapted to snap into place in said groove and having formed integrally therewith a pair of lugs extending into and interlocking with said non-metallic material 100 adjacent said bridge to prevent said metal rim member from snapping out of said groove upon bending of the eyeglasses in use.

In testimony whereof, I have signed my name to this specification this 29th day of September, 1921.

STEPHEN J. CLULEE.
